Frank Schraeder Jr.
Attorney

UNITED STATES PATENT OFFICE.

MARY SKARUDA, OF RIVERSIDE, ILLINOIS.

HAIR DRESS.

Application filed March 19, 1924. Serial No. 700,400.

To all whom it may concern:

Be it known that I, MARY SKARUDA, a citizen of the United States, residing at Riverside, in the county of Cook and State 5 of Illinois, have invented new and useful Improvements in Hair Dress, of which the following is a specification.

This invention relates to a new and useful improvement in a hair dress.

10 Among the objects of this invention is to provide a novel hair dress which can be worn to simulate what is now termed as "bobbed hair". A woman wearing this hair dress need not cut or bob her hair to produce the 15 effect of bobbed hair.

Another object of this invention is to provide a hair dress of this character which permits the removal of the hair from the supporting comb.

20 A still further object contemplates a comb construction which permits attachment of locks of hair in spaced relation to one another; that is, the separate locks of hair may be attached to the desired parts of the 25 comb.

With these and other objects in view, my invention resides in the novel combination and construction of the parts and members shown in the accompanying drawing, 30 described in the following specifications and particularly pointed out in the appended claims.

35 Referring to the drawings in which like reference characters indicate like or corresponding parts, Figure 1 is a view of a hair dress embodying one form of my invention. Figure 2 is a cross section of Figure 1 taken on line 2-2, and Figure 3 is an illustration showing the manner in 40 which the invention may be worn to simulate bobbed hair.

45 Referring to the illustrations, 10 indicates an arcuate comb formed generally of a body of an inverted U cross-section, forming an outer face 10^A and an inner face 10^C.

The outer face 10^A of the comb is provid-

ed with upwardly bent teeth 10^B and the inner face 10^C is provided with downwardly extending teeth 10^D preferably comparatively longer than the teeth 10^B and extending below them. The hair 12 may be inserted in the teeth 10^B in one unit or lock or in separate locks in any desired spaced relation. The teeth 10^D securely hold the comb 10 and the hair 12 in the wearer's hair and 55 in a manner concealing the supporting teeth 10^B.

It will be readily observed by reference to the drawing that the hair 12 could be attached in separate locks A with the B portion omitted, or that the locks of hair indicated by A could be omitted and only the B portion supported from the comb teeth 10^B. In other words, the locks of hair can be supported in the comb teeth 10^B in 60 any desired arrangement.

I claim:

1. A hair dress, comprising a comb having an arcuate body, said body having a set of upwardly bent integral teeth concealed 70 from the outer view of said body, and a second set of teeth integral with said body also concealed from exterior view arranged to support the comb in the wearer's hair, said first named set of teeth adapted to retain locks of hair.

2. A hair dress as embodied in claim 1 and including said locks of hair mounted in spaced relation.

3. A hair dress, comprising a comb having an arcuate body of substantially inverted U-shaped cross-section, the outer face of said body having upwardly bent integral teeth, the inner face of said body having downwardly disposed integral teeth for supporting the comb in the wearer's hair, said teeth on said outer face adapted to retain locks of hair and being concealed from exterior view.

In witness whereof I affix my signature.

MARY SKARUDA.
